ATTORNEY

UNITED STATES PATENT OFFICE

WILLIAM PHILIP KIERNAN, OF EAST ORANGE, NEW JERSEY, ASSIGNOR TO WESTINGHOUSE LAMP COMPANY, A CORPORATION OF PENNSYLVANIA

METALS-REDUCTION BOMB

Application filed April 25, 1928. Serial No. 272,651.

This invention relates to the art of metallurgy and relates more particularly to an improvement in methods of and apparatus for reducing refractory metals as, for example, the calcium-calcium chloride reduction method disclosed by Rentschler and Marden in copending application Serial No. 717,940, filed June 5, 1924, ductile thorium and method of producing the same, and assigned 5 to the same assignee as the present application.

In the reduction of refractory and difficultly reducible metal compounds, particularly those metals which are highly reactive towards gaseous impurities, it is necessary to 15 conduct the reduction reaction in a substantial vacuo. In the process devised and disclosed in the above mentioned copending application, the reduction of the refractory 20 metal oxide is effected by an alkaline earth metal (calcium). An alkaline earth metal halide (calcium chloride) is used as a fluxing medium for promoting the continuation of the reduction reaction to completion. One of 25 the features of this reduction is that at the temperature of the reduction 950° C. the reaction mass is very fluid and the more fluid the mass the more complete the reduction of the refractory metal oxide. In this state of 30 fluidity the corrosive property of the halide flux is at the maximum and no more suitable container has been found than iron, preferably pure iron unalloyed with other intermetallic constituents or with metalloids such 35 as carbon, silicon, etc.

Heretofore it has been customary to make the metals reduction chamber, substantially as described in the above mentioned copending application and usually designated as a 40 "reduction bomb", of cold rolled steel or in the larger type "bombs" of drop forgings of steel, which are usually machined to size.

One of the disadvantages of the use of steel or steel drop forgings has been the expense attending the making of these reduction bombs.

Another objection has been the relatively short life of these steel or iron reduction "bombs" due to excessive surface oxidation 50 and scaling at the temperature to which they

have been heated and to the fact that two closely contacting metal surfaces tend to become welded or bonded together when subjected to elevated temperatures approximating 1000° C.

55

A third objection has been that the steel usually contained carbon or silicious impurities which in the first run or two contaminated the reduced metal powder.

A fourth objection was found in the fact 60 that on effecting reductions in the larger sized "bombs" where a large quantity of metal powders were required on a production basis, difficulty in removing the reduced charge from the "bomb" increased proportionally with the size of the bomb, as such a "bomb" could be made to weigh more than one man could conveniently handle.

65

Another objection was the cost of replacement and costs of upkeep on the larger 70 "bombs".

It is one of the objects of this invention to provide a reduction chamber substantially non-porous and non-oxidizing which will have relatively long life and low maintenance 75 costs.

It is also one of the objects of this invention to provide a material for the inside of the reduction chamber which is substantially non-contaminating to the reduced refractory 80 metal powder.

Another object of this invention is to provide a means of providing the interior of the reduction chamber with a removable non-contaminating sleeve in which the reduced 85 and fused charge may be contained.

Another object of this invention is to provide a method wherein the refractory metal powder is recovered from the fused reduction mass in a simple, expeditious and continuous manner.

90

Another object is to provide a mechanical arrangement of parts in the assembly of the non-porous non-oxidizing reducing chamber, internal non-contaminating sleeve, reduction charge, so that a substantial vacuum can be obtained within the assembly and maintained during the heating of the same to the high temperatures essential to the process and which assembly may be easily and readily 100

taken apart on the completion of the reduction.

Another object of the invention is to provide a bomb, having its component parts so constructed and arranged that they may be assembled and disassembled with convenience and rapidity.

Other objects of the invention will become apparent from the following description, together with the accompanying drawings in which:

Fig. 1 is a side elevational view of a bomb embodying the present invention, portions of the bomb being broken away to more clearly illustrate the internal structure;

Fig. 2 is a view of the under side of the cover of the bomb shown in Fig. 1; and,

Fig. 3 is a plan view of the bomb with the cover and stopper removed.

20 A bomb constructed in accordance with my invention may comprise a chamber 10 preferably in the form of a cylindrical member closed at one end and having an opening 10' to permit the introduction of a charge therein. The opening 10' is provided with a ground tapered seat 12' to receive a ground tapered stopper 12.

For the purpose of applying force to the stopper to hold it in hermetically sealed relation to the seat, means are provided in the form of a protective cap 13. The perimeter of the cap is provided with a plurality of flanges 19 (see Fig. 2) in spaced relation and the perimeter or mouth of the chamber is provided with a plurality of ledges 18 disposed in spaced relation. The cover is so proportioned as to permit the passage of the ledges 18 between the flanges 19 by reason of spaces 14'; when the cover is applied over the mouth of the chamber, the flanges 19 pass between the spaces 14' on the chamber. The cover 13 is provided with an annular recess 17 to permit free movement of the flanges 19 past the ledges 18 whereby the cover may be given a partial rotary movement to frictionally engage the ledges and flanges, thus locking the cover against movement along the axis of the chamber.

50 For the purpose of forcing the stopper against its seat 12' the cover 13 is provided with a movable member in the form of a threaded rod 14 disposed in an elongated threaded aperture 15 in the cover and arranged to coincide substantially with the axial line of the chamber when the cover is in position thereon. A rounded end 15' of the rod is so disposed as to be engageable with a lug 16 integral with the stopper 12. The rod 14 is provided with suitable means as a nut 20 for effecting a rotation of the threaded rod to actuate the same and apply force to the stopper 12, thus pressing the stopper upon its seat and locking it in gas tight relation thereto.

65 According to the present invention the

above described bomb is constructed of a non-oxidizing, heat-resistant material as, for example, an alloy of nickel, chromium and iron similar in property to "nichrome" "hardite", etc. Care should be taken that the castings or forgings be homogeneous in composition and non-porous.

70 The same material should be used throughout in the construction of the bomb otherwise the differences in the coefficient of expansion would permit a separation of one or the other of the parts and the contents of the bomb would be exposed to atmospheric contamination.

75 An important feature of the present invention consists in the provision of what may be termed a liner or container 21 composed of a material non-contaminating with respect to the flux employed in the reduction reaction as, for example, the liner may be of pure iron. The liner 21 may be snugly or loosely fitted to the inner wall of the chamber. It is preferable, however, to make the liner as shown of such dimensions as to be easily removable so that it may be taken out after the 80 reduction has been effected.

85 In practice, the charge to be reduced is tamped down into the pure iron tubing liner and inserted into the reduction chamber and an iron cover may, if desirable, be placed over the mouth of the liner to prevent the reduction charge from splattering, spilling, or from being blown out of the liner during the reduction process. The ground tapered stopper 12 is then carefully applied to the tapered seat 12' and slightly turned to bring the surfaces in complete contact and the protective cover 13 is put in place with the lugs 18 and ledges 19 engaged. Tightening up on the bolt 14 will then effectively lock both the 90 cover and the tapered stopper in position. The bomb is then placed in the furnace, which is preferably of the wire wound resistance type, and heated to 900° to 950° C. for the required length of time. After removing 95 from the furnace and cooling to room temperature the bomb may be opened.

100 The liner containing the reduced charge may then be removed and the stopper quickly reground to fit the taper after which a second liner with a new charge can be inserted in a relatively short interval of time and a second heating made.

105 The liner containing a reduced charge may be placed in a large volume of water to dissolve out the calcium chloride content of the charge and to break down the excess calcium remaining. This is made possible by the fact that the liner (which may be of substantially pure iron as Shelby steel) does not 110 become oxidized on the surface during the reduction process but remains bright and clean and therefore introduces no inert or contaminating oxide impurities in the metal powder product. A sufficiently large volume 115

of water should be employed to counteract the heating effect, due to the energy of solution of the calcium chloride in the water and to the exothermic reaction of calcium metal with water. The evolution of hydrogen, due to the reaction of the excess calcium with water is sufficient to agitate the body of water so as to do away with the necessity of mechanically stirring the water during decomposition of the charge as heretofore practiced. After decomposition the residues are then washed with dilute nitric acid to remove the lime and other soluble salts substantially in a manner as described in the above mentioned copending application.

In using the above described material in the construction of the bomb, the arrangement of parts thereof and the removable liner of non-contaminating metal, the process of preparing difficultly reducible refractory metal powders has been materially simplified and made more efficient and the labor, replacement and time factors greatly reduced.

Although a preferred embodiment of my invention has been described, it is to be appreciated that there may be many ways of varying both the mechanical construction and the materials composing the metals reduction bomb without substantially departing from the nature of my invention but such departures and variations are contemplated as fall within the scope of this invention.

What is claimed is:

A metals reduction bomb composed of a substantially non-oxidizing heat resistant alloy, comprising a chamber having an opening, a tapered stopper for said opening, a seat for receiving said stopper, means for retaining said stopper upon said seat to hermetically seal said chamber and an inner removable liner for said chamber composed of substantially pure iron.

In testimony whereof, I have hereunto subscribed my name this 23rd day of April, 1928.

WILLIAM PHILIP KIERNAN.
